UNITED STATES PATENT OFFICE.

WILLIAM H. WHEELER, OF NEW YORK, N. Y., ASSIGNOR TO FEDCO NUMBER PLATE CORPORATION, OF NEW YORK, N. Y., A CORPORATION OF DELAWARE.

IDENTIFICATION DEVICE AND PROCESS FOR MAKING SAME.

Application filed March 6, 1925, Serial No. 13,491. Renewed June 14, 1927.

This invention relates to an improved identification device and process for making the same which is particularly adapted for the identification of automobiles, although it is not limited to such use.

An object of the present invention is to provide a method by which identification plates can be made quickly and cheaply in large quantities.

10 A further object is to produce an identification plate which cannot be altered without disclosing the fact that it has been tampered with and which cannot be duplicated or counterfeited by an unauthorized person, except at such expense as would be prohibitive or by the use of machinery and equipment involving considerable initial expense and a plant or establishment that would betray a counterfeiter.

20 It is a further object of my invention to provide a plate in which one portion of the indicia is represented in a metal of one color and another portion in a metal of another color, while a third portion is superposed upon one or both of the other two portions.

A still further object is to so form part of indicia that they will be defined by means of marginal depressions.

When two embossing operations are performed on the same plate one embossed design being superposed upon another, it commonly occurs that the first embossed design is so completely flattened or is reduced to so low a relief by the second embossing operation as to be practically obliterated. It is therefore an object of my invention to provide a process whereby a design produced by one embossing operation will not be lost by a superposed design applied by a second embossing.

With these and other objects in view, my invention consists in certain novel features of construction and combinations and arrangements of parts as will be more fully hereinafter described and pointed out in the claims.

In the accompanying drawings:

Figure 1 is a plan view of a fragment of one of my identification devices representing its appearance after being subjected to the first step of my process;

Fig. 2 is an enlarged fragmentary sectional view taken on the line 2-2 of Fig. 1;

Figs. 3 and 4 represent the appearance of 55 the identification plates after having been

subjected to another step of my process, Fig. 3 representing an enlarged sectional view taken on the line 3-3 of Fig. 4, and Fig. 4 being a plan view of a fragment of the plate;

Figs. 5 and 6 represent the appearance of my plate after being subjected to a further step of my process, Fig. 5 being an enlarged sectional view taken on the line 5-5, and Fig. 6 being a plan view of a fragment of the identification plate;

Figs. 7 and 8 are views of my plate after being subjected to a still further step of my process, Fig. 7 being an enlarged cross-section of a fragment of a plate shown in perspective, the section being taken on the line 7-7 of Fig. 8, and Fig. 8 being a plan view of a fragment of the plate;

Figs. 9 and 10 are views of the completed identification plate, Fig. 9 being an enlarged cross-section of a fragment of the plate shown in perspective, the section being taken on line 9-9 of Fig. 10, and Fig. 10 being a plan view of a fragment of the plate.

The body of my identification device consists of a plate formed of two metals of contrasting color. I have found that a base of nickel with a layer of copper applied to the upper face thereof gives very satisfactory results, but it will be clear that my process is not confined to these metals. My process may be satisfactorily used with a wide variety of other combinations such as brass and copper, copper and iron, etc. I propose to use for the identification indicia a name, mark or design, representing the make or model of the car, (hereafter termed the "make indicia") and also a number designating the particular car of said make or model to which the plate is attached, (hereafter termed the "number indicia").

The first step of my process is to emboss upon the plate, a marginal frame and the number indicia. In order to increase the difficulty of altering or counterfeiting a plate, the numbers are applied in Arabic numerals and the name of each numeral is spelled out in alphabetical characters, this name, preferably, being placed above and below each Arabic numeral.

Figs. 1 and 2 illustrate the plate after it has passed through the first step of my process. The body of the plate is indicated by the numeral 10 which for purposes of illustration we shall assume is composed of 105 110

nickel, while superposed on this body is a layer 11 which for purposes of illustration we shall assume, is a layer of copper. In the first embossing operation, the marginal frame 12 is struck up from the background, also the Arabic numerals 13 and the spelled out numbers 14.

It will be observed from an inspection of Fig. 2, that the parts 12, 13 and 14 stand out from the body of the plate, but that the numerals 13 and marginal frame 12 stand higher than the characters 14.

After the plate has been embossed, the second step is to anneal it so that it will be in condition for a second embossing operation to be described later on. This step may be omitted if certain soft metals are employed, but if the body of the plate is of nickel, it is highly important that the plate be annealed after the first embossing operation. The third step of my process is to apply to the embossed face of the plate a liquid material which will harden quickly and form a hard but not too brittle coating 15 over the embossing. This material, however, must be readily soluble so that it can be removed easily in a later step of my process. It is of importance in my process that the material applied to the surface of the plate, be of such viscosity as to form a fairly thick layer and that it possess sufficient surface tension to fill up and form rounded fillets in the re-entrant corners of the embossing. I have found a very satisfactory material for the purpose, to consist of a solution of silicate of soda. Fig. 3 illustrates the plate in section after a layer 15 of silicate of soda has been applied thereto, showing fillets 16 filling the re-entrant angles of the embossed frame and indicia.

The next step of my process is to grind or cut off the embossed face of the plate to such a depth as to remove the copper layer 11 from the frame 12 and numbers 13, exposing the nickel body 10 without, however, removing the copper from the characters 14. This result is shown in Fig. 5. It is desirable that the grinding be carried deep enough to remove the entire coating of silicate of soda from the surface of the characters 14. As shown in Fig. 6, the plate now has the appearance of a copper background with a marginal frame 12 of nickel and with the Arabic numerals 13 standing out in the white metal of the nickel and thereby contrasting sharply with the copper showing through the layer of silicate of soda. All the indicia stand out partly in relief from the copper background of the plate. It will be observed that the indicia and the inner margin of frame 12 are outlined by fillets 16 of silicate of soda and hence the thickness of the silicate of soda along the margins of all indicia is greater than throughout the rest of the plate.

The next step of my process is to emboss the plate with the make indicia; that is a name or design or both, indicating the model or make of car. This step is illustrated in Figs. 7 and 8, wherein the raised characters 17 indicate the name of the car and the raised circle 18 and bars 19 represent a suitable design. In this embossing operation, not only are the name and design raised above the rest of the plate, but the fillets 16 serve to depress the metal along the margins of the numerals 13 and characters 14, and the inner margin of frame 12 as shown clearly in the perspective sectional view of Fig. 7. Thus while the second embossing operation may flatten out the parts that were struck up by the first operation or reduce them to a very low relief, they are not obliterated but are distinguishable by the outlining depressions produced by the fillets 16.

It is desirable that the die with which the second embossing operation is performed be also formed to include a marginal frame coinciding with that with which the frame 12 was formed in the first embossing operation, so that on the second embossing operation the frame 12 will stand up on the same level as, or if desired, even higher than the make indicia.

The next step of the process is to remove the coating 15 including the fillets 16, which may be readily done by washing the plate in warm water. Figure 9 illustrates the appearance of the plate after this has been done. The number indicia 13 show up clearly in contrast with the rest of the plate, because they are of nickel and of a different color from the rest of the surface, and the same is true of the marginal frame 12 which is also of nickel. The make indicia, including the name of the car and a suitable design shows clearly because it is embossed over the rest of the indicia and stands out in relief. However, the number indicia 13 do not depend entirely upon difference of color to make them stand forth clearly from the background; for they are clearly delineated by depressions 20 produced along the margins of the numerals by the fillets 16 which were present during the second embossing operation. The same thing is true of the characters 14 which stand forth with perfect legibility, despite the fact that there is no color contrast between them and the background or the embossed make indicia superposed upon them. Each character 14 is outlined by a depression 20 as clearly shown in Fig. 9. It will be understood of course, that while this depression is sharply defined at the very edge of the numeral or letter it surrounds, the opposite margin of the depression will be rounded and will merge without any sharp definition into the background so that there is no double line effect surrounding the character or numeral. The lines 21

shown in Fig. 9 are introduced merely for clearness of illustration and not to denote a sharp corner.

In order to bring out more strongly the contrast between the Arabic numerals and the rest of the plate so that the number of the car may always be read easily, the plate may now be treated to oxidize the copper surface without discoloring the nickel surfaces. By this operation, the nickel frame 12 and the Arabic numerals 13 are caused to stand out in bright contrast with the rich brown or black surface of the rest of the plate. If desirable the nickel surface may be oxidized or otherwise colored while the copper is left in its natural color.

While I mention silicate of soda as a suitable material for coating the plate and producing marginal fillets, I do not wish to confine myself to the use of this material alone, for it will be evident that many other materials might be used so long as they fill the requirements of having sufficient surface tension to produce substantial fillets in the re-entrant angles of the plate, of solidifying quickly when applied, of not being so brittle as to chip or spall, or so soft as to flow too freely when subjected to the second embossing operation. It is also desirable that the material be readily soluble or otherwise removable after the make indicia has been embossed on the plate. However, it is not essential that the coating material be removed from the plate after the second embossing operation. The coating may remain as a permanent part of the plate, particularly if a transparent coating material be used, such as silicate of soda through which the number indicia may be seen to stand in relief from the background.

It should be noted that the number indicia 13 and 14 stand in low relief above the background because the layer of silicate of soda covering the background holds the latter to a lower level than the surface of the number indicia during the second embossing operation. Hence, I do not rely upon the depressions 20 alone to define the number indicia but preserve said indicia in low relief as contrasted with the high relief of the make indicia. If desirable, the grinding operation need not be carried far enough to remove the coating from the characters 14 in which case, said characters will not appear in relief in the finished plate but will be defined solely by the depressions 20 outlining said characters.

Various slight changes may be made in the steps of my process and the general form and arrangement of the parts described without departing from the invention, and hence I do not wish to limit myself to the precise details set forth, but shall consider myself at liberty to make such changes and alterations

as fall fairly within the spirit and scope of the appended claims.

I claim:

1. A process of producing superposed designs upon a base which consists in (1) embossing one design upon a base, (2) covering the embossed surface with a coating, and (3) embossing a second design over the first design. 65

2. A process of producing superposed designs upon a base which consists in (1) embossing one design upon a base, (2) covering the embossed surface with a transparent coating, and (3) embossing a second design over the first design. 75

3. A process of producing superposed designs upon a base which consists in (1) embossing one design on the base, (2) filling re-entrant corners of the embossing with a filler, and (3) embossing a second design over the first design. 80

4. A process of producing superposed designs upon a base which consists in (1) embossing one design on the base, (2) filling re-entrant corners of the embossing with a filler, (3) embossing a second design over the first design, and (4) removing the filler. 90

5. A process of producing superposed designs upon a base which consists in (1) embossing a design on the base, (2) covering the embossed surface with a coating, (3) embossing a second design over the first design, and (4) removing the coating. 95

6. A process of producing superposed designs upon a plate which consists in (1) embossing a design on the plate, (2) coating the embossed surface with a liquid filler, (3) permitting the filler to solidify, (4) embossing a second design over the coated first design, and (5) dissolving the filler. 100

7. A process of producing superposed designs upon a plate which consists in (1) embossing a design on the plate, (2) coating the embossed surface with a solution of sodium silicate, (3) permitting the coating of sodium silicate to harden, (4) embossing a second design over the coated first design, and (5) removing the coating by dissolving the sodium silicate in water. 105

8. A process of producing superposed designs upon a plate having a body of one metal and a facing of another metal, which process consists in (1) embossing a design on a face of the plate, (2) filling re-entrant corners of the embossing with a filler, (3) removing the facing metal from parts of the design that are in relief to expose the body metal, (4) embossing a second design over the first, and (5) removing the filler. 115

9. A process of producing superposed designs upon a plate having a body of one metal and a facing of another metal, which process consists in (1) embossing a design on the face of the plate, the embossing be-

ing struck up to a high relief and a low relief, (2) filling the re-entrant corners of the embossing with a filler, (3) removing the facing metal from parts of the design which are in high relief, (4) embossing a second design over the first, and (5) removing the filler.

10. A process of producing superposed designs upon a plate having a body of one metal and a facing of another metal, which process consists in (1) embossing a design on the face of the plate, with certain parts of the design in high relief and other parts in low relief, (2) coating the embossed face of the plate with a filler, (3) removing the facing metal from the parts in high relief, (4) embossing a second design over the first, and (5) removing the filler.

11. A process of producing superposed designs on a plate composed of a plurality of laminae of different metals which consists in (1) embossing a design on the face of the plate, the surface of the embossing being struck up to a plurality of levels, (2) coating the embossed surface with a filler, (3) removing the surface metal from one level of the embossing to expose a different metal lying thereunder, (4) embossing a second design over the first, and (5) removing the filler.

12. A process of manufacturing an identification device in which a bi-metallic plate having a body of one metal and a facing of another metal is employed, which process consists in (1) embossing a design on the face of the plate, (2) annealing the plate, (3) filling the re-entrant corners of the embossing with a filler, (4) removing the facing metal from parts of the design standing in relief to expose the body metal, (5) embossing a second design over the first, and (6) removing the filler.

13. A process of manufacturing an identification device in which a bi-metallic plate is employed, which process consists in (1) embossing a design on the face of the plate, certain parts of the design being struck up to a higher level than other parts, (2) annealing the plate, (3) coating the plate with a filler, (4) removing one lamina of metal from the higher level of the embossing to expose the other lamina, (5) embossing a second design over the first, and (6) removing the filler.

14. A process of manufacturing an identification device in which a bi-metallic plate formed with a body of one metal and a facing of another metal is employed, which process consists in (1) embossing a design on the face of the plate, certain parts of the design being struck up to a higher level than other parts, (2) annealing the plate, (3) coating the plate with a filler, (4) removing the facing metal from the higher levels of the embossing to expose the body metal,

(5) embossing a second design over the first, (6) removing the filler, and (7) oxidizing the facing metal of the plate.

15. A process of manufacturing an identification device in which a bi-metallic plate is formed with a body of one metal and a facing of another metal is employed, which process consists in (1) embossing a design on the face of the plate, certain parts of the design being struck up to a higher level than other parts, (2) annealing the plate, (3) coating the plate with a filler, (4) removing the facing metal from the higher levels of the embossing to expose the body metal, (5) embossing a second design over the first, (6) removing the filler, and (7) oxidizing one of the metals showing on the face of the plate.

16. As a new article of manufacture, an identification plate including a surface displaying a background, identifying indicia embossed upon the background, and an embossed design superposed upon the identifying indicia and the background.

17. As a new article of manufacture, an identification plate including a surface displaying a background, identifying indicia embossed upon the background in low relief and an embossed design in high relief superposed upon the identifying indicia and the background.

18. As a new article of manufacture, an identification plate including a surface displaying a background, identifying indicia defined from the background by marginal depressions outlining said indicia, and an embossed design superposed upon the indicia and the background.

19. As a new article of manufacture, an identification plate including a surface displaying a background, identifying indicia inlaid and embossed in low relief on the background, and an embossed design in high relief superposed upon the identifying indicia and the background.

20. As a new article of manufacture, an identification plate including a surface displaying a background, and three classes of identifying indicia embossed thereon, one class appearing in the metal of the background, another class appearing in a contrasting metal, and a third class superposed upon the other two classes.

21. As a new article of manufacture, an identification plate including a surface displaying a background, and three classes of identifying indicia embossed thereon, one class being embossed in low relief, another class also embossed in low relief but displaying another metal, and a third class superposed on the first two classes and embossed in high relief.

22. As a new article of manufacture, an identification plate including a surface displaying a background, and three classes of

identifying indicia embossed thereon, one class being embossed in low relief, another class also embossed in low relief but displaying another metal, and a third class superposed on the first two classes and embossed in high relief, the plate being formed with depressions outlining the indicia of the first and second classes.

23. As a new article of manufacture, an identification plate including a surface displaying a background, and three classes of identifying indicia embossed thereon, one class being embossed in low relief, another class also embossed in low relief but displaying another metal, and a third class superposed on the first two classes and embossed in high relief, the plate being formed with depressions outlining the indicia of the first and second classes, the entire face of the plate with the exception of that forming the second class of indicia being oxidized.

24. As a new article of manufacture, an identification plate including a surface displaying a background, and three classes of identifying indicia embossed thereon, one

class being embossed in low relief, another class also embossed in low relief but displaying another metal, and a third class superposed on the first two classes and embossed in high relief, the plate being formed with depressions outlining the indicia of the first and second classes, one of the metals displayed on the face of the plate being oxidized.

25. In a process of producing superposed designs upon a base, the steps which include embossing a design upon a base, embossing a second design over the first design, and treating the embossed design after the first embossing to prevent obliteration of the design by the second embossing.

26. In a process of producing superposed designs upon a base, the steps which consist in subjecting the base to a plurality of embossings, and treating the embossed surface of the base between each pair of embossings to prevent obliteration of a design formed by one embossing by the next succeeding embossing.

WILLIAM H. WHEELER.
